UNITED STATES PATENT OFFICE.

REYBURN T. CHASE, OF SALT LAKE CITY, UTAH, ASSIGNOR OF ONE-HALF TO FRANK B. SCOTT, OF SALT LAKE CITY, UTAH.

CAN OPENER.

Application filed May 4, 1925. Serial No. 27,951.

One object of my invention is to provide a can opener that can be readily applied to a can, and which will quickly and effectively shear the end of a can close to the edge so that, when the cut portion is removed, the inner surface of the can, at the edge, is smooth and is free of ragged projections, obviating the danger of the user being cut in handling the can, or in removing the contents thereof.

5 A further object of the invention is to provide a can opener with a blunt shearing blade, which does not require sharpening, and which can be drawn into the portion of 15 the can to be cut by the forward movement of the frame, as the traction wheel is rotated.

20 A still further object of the invention is to design the can opener so that the traction wheel is held in gripping contact with the outer bead of the rim of the can during 25 the cutting operation.

In the accompanying drawings:

Fig. 1 is a front elevation of my improved can opener, the blade being turned to allow 25 the opener to be applied to a can;

Fig. 2 is an end view;

Fig. 3 is a plan view;

30 Fig. 4 is a sectional view of a can showing the opener in the act of cutting the end of a can;

Fig. 5 is a sectional view on the line 5—5, Fig. 4, showing the blade in the cutting position;

35 Fig. 6 is a diagrammatic plan view, showing the blade in section on the line 6—6, Fig. 4, making a cut in a can;

Fig. 7 is a diagrammatic sectional elevation on the line 7—7, Fig. 4, showing the front edge of the blade entering the metal 40 of the end of a can; and

Fig. 8 is a diagrammatic sectional elevation on the line 8—8, Fig. 4, showing the rear end of the blade rubbing and pressing down the cut edge of that portion of the end 45 remaining on the body of a can.

The frame 1 is made as shown in the drawings, and has an upper guide 2, which extends over the edge of a can, and a guide 3 that rests against the side of a can so that 50 the frame assumes the proper angle when mounted on a can, as shown in Fig. 5. The toothed traction wheel 4 is located between the two guides 2 and 3 and in a position to engage the rim *b* of a can *a*. The traction wheel 4 is mounted on a shaft 5, which has

its bearing in the frame and is provided, at its outer end, with a handle 6 by which it is turned.

A guide 7 is preferably provided at the forward end of the frame. This guide holds 60 the frame in proper relation to a can so that the traction wheel is not drawn into the body of a can.

Pivotedly mounted at 8 on an upwardly extending portion of the frame is a movable 65 blade 9. This blade has a blunt cutting edge 10. A point 11 is formed by beveling one corner of the blade, as shown in Figs. 1 and 2. The guide 2 acts as a stop for the blade 9, when it is moved into the cutting 70 position, as in Fig. 4.

The pivot 8 for the blade 9 is located, preferably back of a vertical line taken through the center of the cutter.

On referring to Fig. 2 of the drawings, 75 it will be noticed that the blade is arranged at an angle in respect to the traction wheel so that, when the device is mounted on the edge of a can, as in Fig. 4, the wheel is at an angle in respect to the can and the 80 blade 9 is at the inner edge of the rim of the can and slightly inclined towards the body of the can. This insures a clean cut at a point directly back of the rim, and, as the cut is made, the back of the blade presses 85 the cut edge against the body of the can, producing a smooth surface.

The blade 9 is preferably arranged at a slight angle in respect to the face of the traction wheel 4, as illustrated in Fig. 3. 90 This arrangement holds the traction wheel against the can and prevents it running off of the flange of the rim.

The can opener is applied to the can, as shown. The blade 9 is raised, as in Fig. 1, 95 and the frame is mounted on the rim *b* of the can *a*, the guide 2 resting on the upper edge of the rim, and the guide 3 resting against the side of the can, as in Fig. 1. The blade 9 is then turned down so that the 100 point 11 is in engagement with the top or end *c* of the can. This movement forces the traction wheel in contact with the underside of the bead of the rim so that, on turning the wheel in the direction of its arrow, 105 Fig. 5, the frame is moved forward, while the point of the blade is forced into the top *c* of the can, and, as the movement continues, the desired shear cut is made, as shown in Figs. 5, 6 and 7. The turning movement of 110

the blade is limited by its engagement with the guide 2. As the cut is made, the rear inner portion of the blade presses against the cut edge and forces it against the body 5 α of the can, as shown in Figs. 6 and 8, making a smooth finish. The opening in the can, after the cut top is removed, is substantially the full diameter of the can. After the complete cut is made, the frame 10 can be readily detached from the can on raising the blade.

I claim:

1. In a can opener, the combination of a frame; a traction wheel on the frame arranged to engage the underside of the rim of the can; a shear blade pivotally mounted on the frame and arranged to be moved into contact with the metal of the can so that on the first movement of the traction wheel the blade will be forced through the metal of the can; and a stop to limit the movement of the blade so that as the movement of the wheel continues a shear cut is made.
2. In a can opener, the combination of a frame having a top guide and a side guide; a traction wheel arranged to engage the underside of the rim of the can; and a blade pivotally mounted on the frame and so arranged that when the blade is in contact with the metal of the can, the first forward movement of the traction wheel will cause the blade to puncture the can, and as the movement continues the blade will shear the metal of the can.
3. In a can opener, the combination of a frame having a top guide and a side guide; a traction wheel mounted on the frame between the two guides and arranged to engage the underside of the rim of the can; and a cutting blade pivotally mounted on the frame and having a penetrating portion and a diagonal cutting edge, so that when the traction wheel is turned, the penetrating portion of the blade will first puncture the can and the cutting edge will shear it.
4. In a can opener, the combination of a frame; means for moving the frame in respect to the can to which it is applied; and a shear blade pivotally mounted on the

frame, said blade being arranged so as to 50 make a shear cut close to the beveled edge of the can, the rear of the blade being so positioned as to press the cut portion against the body of the can.

5. In a can opener, the combination of a 55 frame having a top guide and a side guide; a traction wheel arranged to engage the lower edge of the bead of a can; means for rotating the wheel; a forward guide on the frame arranged to rest against the bead of 60 a can, and a blade pivotally mounted on the frame and having a beveled corner, said blade being arranged to first puncture the can and then cut the metal of the can as the wheel is turned.

6. In a can opener, the combination of a 65 frame having a top guide and a side guide; a traction wheel mounted on the frame; means for turning the traction wheel; and a blade pivotally mounted on the frame, said blade having a beveled portion to puncture the can upon the first movement of the traction wheel, and as the movement of the traction wheel is continued, the blade will cut 70 the can, said blade being arranged at an angle in respect to the face of the traction wheel.

7. In a can opener, the combination of a frame; guides thereon; a traction wheel arranged to engage the can; and a cutting 80 member pivotally mounted on the frame, said member having a point at one corner for the initial piercing of the metal of the can, and having an oblique shearing edge for cutting the can after it has been pierced.

8. In a can opener, the combination of a frame arranged to be applied to the edge of the can to be opened; a blade pivotally mounted on the frame, said blade having a point and a cutting portion; a stop on the 90 frame to limit the movement of the blade when said blade has been turned after puncturing the can, so that the cutting portion of the blade will be at an angle to the surface of the can so that the blade will make 95 a shear cut as the movement of the traction wheel is continued.

REYBURN T. CHASE.
